MANUFACTURING COMPANY, OF DUNEDIN, FLORIDA, A CORPORATION OF FLORIDA.

BOX-PRESS.

1,150,639.

Specification of Letters Patent. Patented Aug. 17, 1915.

Application filed August 14, 1914. Serial No. 856,768.

To all whom it may concern:

Be it known that I, BRONSON C. SKINNER, a citizen of the United States, and a resident of Dunedin, in the county of Pinellas and State of Florida, have made certain new useful Improvements in Box-Presses, of which the following is a specification.

My invention more particularly relates to a clamping press for the tops of crates used 10 in packing and shipping citrus fruits such as oranges, lemons and grapefruit.

It is well known to those engaged in packing citrus fruits that they are packed with a so-called "bellied" top, the fruit projecting 15 somewhat above the upper edges of the crate over which the flexible top or cover is placed, and flexed downwardly so that the ends of the cover may be nailed to the crate, the central portion of the cover bulging outwardly 20 and upwardly and disclosing the fruit along the sides. The object of so packing citrus fruits is to insure that there shall be no movement of the contents of the crate during shipment, the yielding pressure of the 25 flexed cover firmly holding the fruit against all movement. In addition to securing the cover at the ends, it is customary to apply a box strap of metal or hickory, or other tough wooden strip, transversely about the 30 central portion of the crate and over the cover. Because the crate is packed with this bulging or "bellied" top, it is customary in packing houses handling citrus fruit to employ a box press having clamps to engage the 35 ends of the cover and to draw them downward to contact with the upper edge of the crate at the ends and to hold the cover in place while being nailed or otherwise secured.

The object of the present invention is to 40 provide a box press having clamps so constructed and operated that they will not interfere with the handling of the crate and its proper positioning on its support, the 45 clamps having such movements that when disengaged from the crate they are in a position whereby they will not interfere with the positioning of the crate.

A further object of the invention is to so 50 construct the operative instrumentalities that a free clearance space is provided and the clamping mechanism will not interfere with the positioning of the central transverse strap or band, and whereby the strap or band may be positioned and applied 55 without releasing the clamping devices from

engagement with the top of the crate, there being no part of the clamping mechanism to interfere with the positioning and drawing of the box strap about the crate or the movements of the hands of the operator while applying the box strap.

To the above ends my invention consists of a box press comprising a support for the crate or box and with clamping members located at or near the ends of said support, 65 and each provided with independently operating mechanism to control the movements of the clamping members into and out of clamping position, and a common operating device for said clamping members located 70 below the surface of the table or support.

My invention further consists of the devices and combinations of devices which will be hereinafter described in the claims.

My invention is illustrated in the accompanying drawings in which—

Figure 1 is a perspective view illustrating my invention with a box in place upon the receiving table and the clamping members in inoperative position, Fig. 2 is a front elevation, partly broken away and in section, illustrating the clamping members in clamped position upon a box, Fig. 3 is a side elevation, Fig. 4 is a horizontal section taken substantially on line 4—4 of Fig. 3, 85 and Fig. 5 is a detail perspective view illustrating certain parts to be hereinafter specifically referred to.

The apparatus as illustrated in the drawings comprises a suitable frame consisting of 90 the vertically disposed end frames A and the horizontally disposed receiving table B, the table B being rigidly secured in any suitable manner to the tops of the end frames A, and in practice the end frames A will be 95 bolted to the floor or other support by the bolts a. The end frames A are preferably of such height that when bolted to the floor the table B will be positioned at a convenient height above the floor to facilitate the 100 positioning of the crate thereon as the same is taken from the end of the runway by means of which the filled crates are brought to the operator who applies the tops or covers thereto. The upper surface of the 105 table B is preferably smooth from end to end, and preferably along the back edge it will be provided with a narrow vertically extending flange C which affords a guide against which the rear lower edge of the 110

crate may be positioned in placing the crate on the table. The clamping members comprise a pair of angular levers, each having a carrying portion F and a clamping portion F¹ extending from the upper end of the portion F and preferably disposed at right angles thereto. The clamping levers are each independently supported at or near the ends of the table B in such manner that they may have upward and downward movements for the purpose of causing the clamping portions F¹ to move away from and toward the top of the box or crate, and in the apparatus of the drawings they are so supported that in their upward and downward movements they will have a movement backward and forward, away from and toward a vertical plane extending through the table B, so that the clamping portions F¹ when released move upward and backward out of the way of the operator leaving a free clearance space for the removal and reception of the crates from and on the table B, and in the clamping movement they move inward and downward toward the top of the box or crate. The supporting mechanism shown in the drawings comprise links G which are pivotally connected at their ends respectively to the lower forwardly extending ends of the carrying portions F and to the side frames A as by means of the bolts g. The clamping members are also connected to links I which at one end are pivotally connected by means of the bolts i to the carrying portion F of the clamping members and at their opposite ends by means of bolts h to upwardly and rearwardly extending brackets H projecting from the end frames A. It will be noted that the supporting devices of each of the clamping members is entirely independent of the supporting devices of the other clamping member, and that except for the operating mechanism which imparts the upward and downward movement to the clamping members they are not connected with each other, and thus a free and unobstructed space is provided between the clamping members at the rear of the table so that they will not interfere with the manipulation and application of the box strap to the central portion of the crate. The operating instrumentalities which impart vertical movements to the clamping members include a reciprocating crosshead D² which carries a rod or shaft E, and which shaft at each end engages an aperture f in the lower forwardly extending ends of the carrying portions F of the clamping members. The crosshead D² imparts a simultaneous downward movement to the clamping members and for this purpose it is provided with a link D which is pivotally connected at its upper end to the crosshead D² and at its lower end pivotally connected to a foot treadle D¹. The crosshead is de-

pressed against the tension of springs J, there being two such springs which at their lower ends are supported by brackets j upon the inner faces of the end frames A and at their upper ends engage and are connected to lugs m projecting from the lower ends of the carrying portions F. The springs J act to elevate the cross heads D² and the clamping members F when the foot treadle is released. It is to be observed that the links G and I are so positioned and so connected to the carrying portions F of the clamping members that when they are moved vertically by means of the crosshead D² and the springs J they at the same time move into and out of a vertical plane, and thus the clamping portions F¹ are moved into and out of a plane which will cause them to engage the ends of the cover which is to be applied to the crate. It will be further noted that when elevated and moved out of the clamping plane, the clamping portions F¹ are disposed in such a manner that a relatively large free clearance space is provided for the positioning of the crate on the table B, the clamping members where they project above the table being located entirely at the rear thereof so that the crate may be slid on to the upper surface of the table from one end as it is taken from the conveyor which delivers the filled crates from the packing table. It will be further noted that the apertures f are flaring at each end, forming a rounded bearing permitting a slight relative rocking movement of the clamping members with relation to the ends of the shaft E, so that the clamping members may adjust themselves to the height of the crate at the ends, even though there be slight variations in height by means of this rocking connection of the crosshead D² with the clamping members which provides for a limited independent clamping movement of the clamping members.

In operation a box strap is positioned transversely on the table B and the crate placed thereon. The flexible cover is then laid on the fruit and the treadle D¹ depressed, thus through the link D imparting a downward movement to the crosshead D², which by means of the shaft E causes a downward movement to the clamping members against the tension of the springs J, and as the clamping members move downward they are by means of the links G and I caused to move first toward the crate or toward the table, so that the carrying portions F are disposed in a vertical plane and the clamping portions F¹ in a horizontal plane, and the further downward movement brings the clamping portions F¹ into contact with the ends of the flexible cover depressing the ends over the fruit and bringing them into contact with the ends of the crate, in which position the cover will be

held by the clamping members while the operator nails the cover to the crate at the ends. Thereafter the operator releases the foot treadle D^1 and the springs J , raising the crosshead D^2 , move the clamping members upwardly and rearwardly as shown in Fig. 3 in full lines, (the dotted lines in Fig. 3 showing the clamping position), thus leaving a free and unobstructed space for the operator in drawing the ends of the box strap about the crate and fastening it in the usual manner.

Having described my invention I claim as new and desire to protect by Letters Patent of the United States:

1. A box press comprising a table or support, clamping members disposed near each end thereof and extending above the table at the back thereof, means for imparting vertical movements to said clamping members, and means to cause said clamping members to swing transversely in parallel vertical planes toward and from a vertical plane during their vertical movements.
2. A box press comprising a table or support, angular clamping members extending upwardly at the back of said table or support, pivotally mounted toggle links pivotally connected with said clamping members, a vertically movable crosshead engaging the lower ends of said clamping members, means to move said crosshead, and springs engaging said clamping members.
3. A table or support, independently supported clamping members extending upwardly at the rear thereof, a crosshead for operating said clamping members, and a rocking connection between said crosshead and said clamping members.
4. A box press comprising a frame including a box receiving table, clamping members normally inclined upwardly and rearwardly at the rear and above the said table and each formed in one piece and provided with an upper forwardly extending clamping portion, and a lower end inturned forwardly beneath the table, links pivotally connecting the said inturned lower ends of the clamping members to the forward portion of the frame, links pivotally connected at their rear ends to the rear portion of the frame and at their forward ends to the said clamping members above the lower inturned ends of the latter, whereby to form working fulcrums for the clamping members, treadle operated connections engaging the said lower inturned ends of the clamping members, and springs depending from the said lower inturned ends of the clamping members and seated upon portions of the frame to return the members when the said treadle operated connections are released.
5. A box press comprising a frame including a box receiving table, clamping members normally inclined upwardly and rearwardly at the rear and above the said table and each formed in one piece and provided with an upper forwardly extending clamping portion, and a lower end inturned forwardly beneath the table, links pivotally connecting the said inturned lower ends of the clamping members to the forward portion of the frame, links pivotally connected at their rear ends to the rear portion of the frame and at their forward ends to the said clamping members above the lower inturned ends of the latter, whereby to form the working fulcrums for the clamping members, treadle operated connections engaging the said lower inturned ends of the clamping members, and springs to return the members when the said treadle operated connections are released.
6. A box press comprising a frame including a box receiving table, upright clamping members at the rear of the table, said members being in one piece and having upper clamping portions and lower ends inturned beneath the table, links pivotally connected at their forward ends to said clamping members and at their rear ends to portions of the frame, other links pivotally connected at their rear ends to the inturned lower ends of the clamping members and at their forward ends to forward portions of the frame, and treadle operated connections loosely engaging said lower inturned ends of the clamping members.
7. A box press comprising a frame including a box receiving table, clamping members extending upright at the rear of the receiving table and having upper clamping portions, and vertically shifting fulcrums intermediate their ends, said clamping members having lower inturned ends extending beneath the table and pivotally connected to forward portions of the frame, and treadle operated connections loosely engaging said inturned ends of the clamping members.
8. A box press comprising a frame including a box receiving table and clamping members extending upwardly at the rear portion of the said table, links pivotally connecting the said clamping members to the forward and rear portions of the frame and spaced vertically in the length of the clamping members, and treadle operated connections loosely engaging the lower ends of the said clamping members.
